Claims priority, application Austria Apr. 22, 1961

Term of patent 3½ years

(Cl. D54—12)

FIG. 1 is a front elevational view of a spoon showing my new design;

FIG. 2 is a side elevational view thereof; and

FIGS. 3, 4 and 5 are sectional views thereof taken on the lines 3—3, 4—4, and 5—5 of FIG. 1.

The dominant feature of my design resides in the combination on the spoon disclosed of the specific decoration engraved in the handle portion, all as shown.

I claim:

The ornamental design for a spoon, as shown and described.
